CLAIM

We claim the ornamental design for a syringe pump, as shown and described.

DESCRIPTION

FIG. 1 is a perspective view of a syringe pump.

FIG. 2 is a front elevation view of the syringe pump.

FIG. 3 is a rear elevation view of the syringe pump.

FIG. 4 is a side elevation view of the syringe pump.

FIG. 5 is another side elevation view of the syringe pump, from the side opposite that in FIG. 4.

FIG. 6 is a top plan view of the syringe pump; and,

FIG. 7 is a bottom plan view of the syringe pump.

(Continued)

The dashed broken lines depict portions of the syringe pump that form no part of the claimed design.
